UNITED STATES PATENT OFFICE.

EDWIN G. STAUDE, OF MINNEAPOLIS, MINNESOTA, ASSIGNOR, BY MESNE ASSIGNMENTS, TO UNITED STATES ENVELOPE COMPANY, OF SPRINGFIELD, MASSACHUSETTS, A CORPORATION.

ENVELOP-MACHINE.

1,193,626.

Specification of Letters Patent.

Patented Aug. 8, 1916.

Application filed October 21, 1912. Serial No. 727,001.

To all whom it may concern:

Be it known that I, EDWIN G. STAUDE, a citizen of the United States, and resident of Minneapolis, in the county of Hennepin, 5 State of Minnesota, have invented certain new and useful Improvements in Envelop-Machines, of which the following is a specification.

My invention relates to machines for making envelopes of various sizes and the object 10 of the invention is to provide improved means for applying glue to the side flap of the blank that is stuck to the end flaps and also in gluing the edge of the loose flap 15 which is afterward used for closing the envelop.

A further object is to provide a gluing mechanism capable of convenient and rapid adjustment to adapt the machine to various 20 sizes of envelopes.

A further object is to apply glue to the envelop flaps in such a way that it will be evenly distributed and without smearing the inner portions of the flaps or the body 25 of the envelop, or applying so much glue that it would squeeze out between the flaps when pressure is applied thereto and cause the envelopes, when stacked, to stick together or present an unsightly appearance.

30 My invention consists generally in various constructions and combinations, all as hereinafter described and particularly pointed out in the claims.

In the accompanying drawings forming 35 part of this specification, Figure 1 is a plan view of an envelop machine embodying my invention, Fig. 2 is a detail sectional view of the gluing mechanism, Fig. 3 is a partial plan view of the same, Fig. 4 is a side view 40 of the sectional roll by means of which the glue is applied to one of the side flaps, Fig. 5 is a plan view of the same, Fig. 6 is a detail sectional view, on the line $x-x$ of Fig. 4, illustrating the manner of mounting the 45 sections of the roll on the shaft, and the device for moving the flap into contact with the glue points, Fig. 7 is a detail view in perspective, illustrating the adjustable feature of the roll sections with respect to one another, Fig. 8 is a detail view, showing the manner of mounting the glue points or plugs in the peripheries of the sections, Fig. 9 is a plan view of a gluing roll illustrating a modified construction, Fig. 10 is an end view 50 of the same, Fig. 11 is a sectional view on

line $y-y$ of Fig. 10, Fig. 12 is a detail view of an envelop blank, showing the glued edges of the side flaps.

In the drawing, 2 represents the feeding mechanism of the machine and 3 the mechanism for feeding, creasing and folding the end flaps of the envelop blank.

4 is a secondary or supplementary feeding mechanism arranged to receive the blanks from the primary feeding and creasing 45 mechanism and advance them in a direction at right angles substantially to their original movement. Near this secondary feeding mechanism I provide a gluing device for the blank, which forms the subject-matter of 70 my present application.

At the discharge end of the secondary feeding mechanism I provide creasing rolls 5 adapted to crease the blank lengthwise at the point where the side flaps are joined to 75 the main portion of the envelop. Above these rolls the frame is provided with a cross bar 6 adapted to support brackets 7 between which a glue-pot 8 is suspended. A glue-roll 9 is journaled in the frame of the machine and depends within a pan 10 which is preferably provided with a curved bottom 11 having holes 12 therein and adapted to receive the roll 9. A scraper 13 is mounted on said pan and is adapted to bear on the 80 roll 9 and prevent the accumulation of too much glue on the surface of the roll. The pan 10 is adapted to move back and forth in the glue-pot and is preferably operated by 85 means of threaded rods 14 having adjusting nuts 15. A roll 16 is arranged to bear on the surface of the roll 9 and is carried by brackets 17, also supported by the cross bar 6. This roll 16 contacts with the roll 9 and receives a sufficient amount of glue therefrom for application to the gluing points or 90 plugs, as will hereinafter appear.

18 and 19 represent upper and lower shafts on which pulleys 20 and 21 are secured. On these pulleys or wheels feed belts 22 and 23 are mounted and between which the blanks are delivered from the creasing rolls 5. At this point in the manufacture of the envelop the end flaps 24 will have been creased and folded and after passing the creasing rolls 5 the side flaps 25 and 26 will be creased, ready to have their edges glued preparatory to the last step in the manufacture of the envelop.

Mounted on the shaft 18 is a hub 24' pro-

vided with an arm 25' supporting a curved wing or plate 26'. This wing has an outer gluing surface 27 that is adapted to contact with the surface of the roll 16 and to receive a supply of glue therefrom in the operation of the machine. The wing is preferably made with a crescent-shaped gluing surface and corresponds to the edge of the loose flap of the envelop to which it is desired to apply the glue, and when the envelop passes in between the feed belts the loose flap is moved into contact with the gluing wing to apply a sufficient quantity of glue thereto to gum the sealing flap of the envelop. To insure contact of this sealing flap with the gluing surface I prefer to mount a stud 27' on the frame 28 to support a clamp 29 which is adjustable lengthwise of said stud and also circumferentially with respect thereto, and supports a pipe 30 connected with a source of air under pressure and extending under the gluing surface 27 and provided with a narrow slot 31 through which currents of air are blown to swing the loose flap 26 into contact with the gluing surface 27 and apply a sufficient quantity of glue to the edge of the flap to insure the sealing of the envelop when used. On the other side of the machine a similar device is provided for lifting the flap 25. These pneumatic devices being substantially the same, I will designate them by the same reference numerals.

I may prefer to apply a cheaper quality of glue to the flap 26 than to the flap 25, and I am able to do this by the independent arrangement of the glue rolls 9 and 9', which may operate in separate compartments of the glue pan, separated by the partition 9'', as indicated in Fig. 3.

The device for applying glue to the flap 25 may be made in various ways. I prefer, however, to use the device illustrated in Figs. 4 to 8 of the drawings, and which I will now describe in detail. 32 represents a sleeve, splined on the shaft 18 and adjustable longitudinally thereon by means of the set screw 33, which operates against the spline to press it firmly against the bottom 50 of the groove of shaft 18. The hub 24' is also adjustable on this shaft, so that the gluing devices may be moved nearer to one another or farther apart, to adapt them for envelops of different sizes. One end of the sleeve 32 is provided with an annular flange 34 and the opposite end of the sleeve is threaded to receive a lock nut 35. Between this flange and lock nut I provide a series of segments 36 having hubs 37 provided 60 with rabbeted edges 38 to allow the hubs to nest or interlock with one another on the sleeve 32. The hubs operate to hold the segments in place on the sleeve and allow them to be rotated for the different adjustments of the gluing surfaces. The ends of

the segments are adapted to lap by one another, as indicated at 39, to allow their rotary adjustment on the sleeve, and each segment is provided with a gluing point or plug 40 fitting a socket 41 in the periphery 70 of the segment and projecting slightly beyond the peripheral surface and adapted to receive glue from the roll 16 for application to the envelop flap 25. These gluing plugs are preferably arranged, (as indicated 75 in Fig. 5) in diverging rows running crosswise of the segments to adapt them for application of the glue to the edges of the flap. The segments are preferably provided with curved slots 42 to receive bolts 43 by means 80 of which the segments may be held in their locked relation. Each set of segments has a locking bolt so that all of the segments may be loosened on the sleeve for rotary movement and then by loosening one of the 85 bolts 43 the segments secured together by that bolt may be adjusted with respect to the corresponding segments, which are still held locked together by the other bolt. I am thus able to easily and quickly adjust 90 the rows of gluing points toward or from each other to adapt the device for different lengths of flap and different shapes thereof. The plugs 40 may be made of any suitable material, preferably rubber, and 95 will apply the glue to the edges of the flap, as indicated in Fig. 12.

In Figs. 9, 10, and 11 I have shown a modified construction of the device for applying glue to the edges of the flap 25. 100 This device consists of a hub 44 mounted on the upper shaft 18 and provided with an annular flange 45 at one end, between which and a plate 46 secured by adjusting screws 47 to the other end of the hub, a series of 105 segments 48 are arranged. These segments are arranged in groups, as in the preferred construction, with a space provided between the adjacent ends of the groups, and this space is bridged by a series of rings 49 which are arranged between the abutting edges of the segments and extend entirely 110 around the hub, being held thereon by the pressure of the segments upon one another. Upon loosening the bolts 47 pressure on the 115 segments will be relieved and they may be adjusted endwise between the rings to adapt the gluing points corresponding to those described in the preferred construction for the different sizes of envelop flaps. The 120 outer segments are preferably made wider at the base to fit the recess in a portion of the flange 45 and an annular groove 50 in the face of the plate 46.

In the operation of the machine, blanks 125 with folded end flaps are delivered to the scoring rolls 5 and the blanks creased lengthwise, thereby forming the side flaps. As the blank passes between the belts 22 and 23, the side flaps will be blown upward by the 130

currents of air in the pipes 30 and into contact with the gluing surface 27 and with the gluing points 40, whereupon a sufficient quantity of glue will be applied to the edges 5 of the flaps to secure the flap 25 to the flaps 24 and complete the envelop while the flap 26 will seal the envelop when its gummed edge is moistened.

I make no claim herein to the above described constructions of the devices for applying glue to the flap 25. Said devices are fully described and claimed in my copending application, Serial No. 748,346, filed Feb. 14, 1913.

15 I claim as my invention:—

1. The combination, with the upper and lower feed belts for forwarding an envelop blank, of a gluing roll disposed near one edge of said belts, an angular wing having a 20 gluing surface disposed near the opposite edge of said belts, means for applying glue to said roll and said wing, and means for holding the envelop flaps against the surfaces of said roll and wing as the body of 25 the blank is carried between said feed belts.

2. The combination, with coöperating upper and lower feed belts for forwarding envelop blanks, said blanks having flaps projecting laterally beyond the outside edges of 30 said belts, of gluing devices disposed outside the lateral edges of said belts in the paths of said projecting flaps, and means for yieldingly pressing said flaps against said gluing devices.

3. The combination, with the upper and lower feed belts and pulleys and shafts therefor, of a gluing roll disposed near one edge of said belts, a wing having an angular curved surface disposed near the other edge 40 of said belts, means for applying glue to said roll and surface, and slotted pipes arranged beneath said roll and wing and adapted to direct air under pressure upwardly toward said roll and wing, for the 45 purpose specified.

4. The combination with pairs of upper and lower feed belts for forwarding envelop

blanks, each blank having a flap projecting beyond the outside lateral edges of one of said pairs of belts and on the opposite side 50 thereof from said other pair of belts, a gluing device disposed in the path of said projecting flap, and means for yieldingly pressing said flap against said gluing device.

5. The combination, with the upper and lower feed belts and shafts and pulleys therefor, of a gluing roll mounted on one of said shafts near one edge of said belts, a gluing wing mounted on the same shaft near the other edge of said belts, means for applying glue to the surface of said roll and wing, studs mounted adjacent to said roll and wing, pipes having slots therein carried by said studs and adjustable thereon and communicating with a source of air under 65 pressure, said pipes directing currents of air to said roll and gluing surface to hold the envelop flaps in contact therewith.

6. The combination, with the upper and lower feed belts and pulleys and shafts 70 therefor, of a gluing roll mounted to revolve near one edge of said belts, a gluing wing mounted to revolve near the other edge of said belts, said roll and wing operating to gum the longitudinal flaps of an 75 envelop passing between said belts, and means for applying glue to the surfaces of said roll and wing.

7. The combination, with an envelop feeding means between which the body of the envelop is fed, the side flaps projecting laterally beyond each edge of said feeding means, gluing devices arranged laterally with respect to said feeding means and between which said side flaps extend, and a pneumatic device for temporarily pressing said flaps upwardly into contact with said gluing device.

In witness whereof, I have hereunto set my hand this 17th day of October, 1912.

EDWIN G. STAUDE.
